UNITED STATES PATENT OFFICE.

JOSEPH G. SAVAGE, OF BROOKLYN, ASSIGNOR TO PATTERSON & GREENOUGH, OF NEW YORK, N. Y.

DESIGN FOR A SHAWL.

SPECIFICATION forming part of Design No. 13,864, dated April 17, 1883.

Application filed February 7, 1883. Term of patent 14 years.

To all whom it may concern:

Be it known that I, JOSEPH G. SAVAGE, of Brooklyn, Kings county, New York, have invented and produced a new and original Design for Shawls, of which the following is a specification, in connection with the accompanying drawing.

My design applies more especially to double-square shawls, but is not necessarily confined thereto, as it may also be applied to single-square shawls, and it belongs to that class of designs in which one half of the shawl has a distinct figure from the other half, the figuring being of a plaid character.

15 In the drawing annexed, the figure presents the plan of an outspread double or square shawl figured with my present design.

In this drawing, *a a* indicate a series of closely-adjoining parallel stripes, which run lengthwise or warpwise the whole length of the shawl, as shown. These warp-stripes are crossed at one end of the shawl by transverse stripes *b b*, which are preferably of identical character with the warp-stripes *a a*, and they 20 preferably extend over one half of the shawl, as shown, thus giving one square or half of the shawl a checked figure. The opposite end or half of the shawl is, however, crossed at intervals by diverse stripes *d d*, 25 which are preferably of a wide, bold, and decidedly-different character from the warp-stripes *a a*, so that while an oblong checked effect is produced by the intersection of the warp-stripes *a a* with the wide diverse stripes 30 *d d*, yet to ordinary observation at a distance these oblong checks, as well as the warp-stripes, are not conspicuous, but the shawl presents the appearance of a strong, boldly-striped field on one half and a fine-checked 35 field on the other half. At the same time the intersection of the bold diverse stripes *d d* by the close regular warp-stripes gives a soft blended effect to the striped field, which is pleasing to the eye. The warp-stripes *a* and 40 the cross-stripes *b b* in the checked half of the shawl are preferably of a prismatic or shading character, which gives a very soft blended effect to the checked field, and greatly reduces the sharp, abrupt character of ordinary checking, as will be readily appreciated.

It will be seen that a shawl figured as illustrated may be so folded and worn as to pre-

sent different appearances at different times—that is, it may present the appearance of a checked shawl or a striped shawl, according to whichever half of the shawl is turned outward, thereby enabling the wearer to obtain a variety of appearances from the same garment, and thus increasing its dressy value. 55

I do not confine myself to the precise character of the individual stripes shown, as it will be obvious that these may be varied in many ways without departing from the characteristic effect of the design. 55

My design is not limited to any special coloring; but I would mention that one half of the longitudinal warp-stripes *a* might be of a different color, and also of a different form, from the other half, and the cross-check stripes *b* 70 might be of a different color from the bold stripes *d d*. I would also mention that the longitudinal stripes *a a* might terminate at the middle of the shawl, so as not to traverse the bold stripes *d d*. These modifications 75 would not materially alter the general character of the design, which consists in a field of close checks on one half of the shawl and a field of positive stripes on the other half, as illustrated. 80

What I claim is—

1. The design set forth for a double square or medially-divided shawl, consisting of a field of close checks covering one half of the shawl and a field of positive contrasting stripes covering the other half of the shawl, substantially as described and illustrated. 85

2. The design for a shawl, consisting in a closely-striped warp crossed on one half by similar stripes forming checks and on the other half by diverse stripes, giving a distinct striped effect, substantially as herein described and illustrated. 90

3. The design for a shawl, consisting in a close series of longitudinal or warp stripes having a shaded or prismatic character, with a series of similar stripes crossing the same over one half of the shawl and a series of diverse stripes crossing said longitudinal stripes over the other half of the shawl, substantially 95 as specified. 100
